UNITED STATES PATENT OFFICE.

RUDOLF WM. VON SYDOW, OF GLENDALE, CALIFORNIA, ASSIGNOR OF ONE-HALF TO
EDWARD G. BURGHARD, OF LOS ANGELES, CALIFORNIA.

BOTTLE CAP.

Application filed August 23, 1926. Serial No. 130,962.

This invention relates to a cap for bottles, an especially to paper caps adapted to serve as a covering for large mouthed bottles, such as milk or cream bottles.

5 Milk bottles are now quite commonly provided with pasteboard or paper disks, for serving as a stopper. This disc is retained by friction against the inner walls of the bottle neck, and rests on a shoulder 10 therein. It is commonly known that such a cap is hard to remove when it is desired to pour from the bottle; and the likelihood is that when so removed, it is either torn or twisted to such an extent that it cannot 15 again serve efficiently as a cap. Since the housewife often has occasion to store-away bottles only partly filled, the impracticality of utilizing the cap for the bottle often results in it being left off entirely, with 20 consequent danger of contamination of the milk.

That danger, of course, is also present when taking the cap off; for it often happens that the cap is jammed down into the neck 25 of the bottle and into the milk, and must be recovered by the fingers or other means.

I am aware that various other kinds of caps have been suggested to overcome these disadvantages; for example, metal caps, such 30 as are in common use for beverage bottles are used. But these are expensive and difficult to replace. Still another kind of cap has a flange that rests over the bead at the bottle mouth; but this form requires special 35 treatment for holding it in place in the mouth, and due to this complication, it is expensive to manufacture.

It is one of the objects of my invention to 40 provide a bottle cap that can be inexpensively produced, and readily and easily removed and replaced without injury by the housewife.

It is another object of my invention to 45 provide a bottle cap that can be placed on a bottle with substantially the same bottling apparatus as is now in common use.

It is sometimes desired, in connection with 50 certified milk, to provide a cap or cover that cannot readily be removed without tearing or permanently altering the appearance of the cap, whereby a purchaser is assured that when milk is purchased with such a cap intact, it has not been tampered with by unauthorized persons. It is still another ob-

ject of my invention to provide a cap for 55 certified milk bottles that has all these advantages, and yet can be produced at little more expense than the ordinary disk-like closure.

It is still another object of my invention 60 to provide a bottle cap that is held in place by suction, as by the provision of a series of depressions, serving as vacuum cups co-operating with the upper surface of the head around the bottle mouth. 65

My invention possesses many other advantages, and has other objects which may be made more easily apparent from a consideration of several embodiments of my invention. For this purpose I have shown a 70 few forms in the drawings accompanying and forming part of the present specification. I shall now proceed to describe these forms in detail, which illustrate the general principles of my invention; but it is to be 75 understood that this detailed description is not to be taken in a limiting sense, since the scope of my invention is best defined by the appended claims.

Referring to the drawings: 80

Figure 1 is a sectional view of a bottle cap embodying my invention, shown in proper sealing relation with a milk bottle;

Fig. 2 is a top plan view thereof;

Fig. 3 is a side elevation of a cap for 85 certified milk bottles, embodying my invention, and shown as installed on a bottle;

Fig. 4 is a bottom plan view of the cap shown in Fig. 3; and

Fig. 5 is a partial development, showing 90 the form of blank that may be used for making the cap of Figs. 3 and 4.

In Fig. 1, I show a bottle 11, having the usual bead or enlargement 12 at the mouth. Inside the mouth there is a narrow shoulder 95 13, upon which usually rests the old form of disc-like closure or cap. The mouth of the bottle 11 forms the interior vertical surface 14.

In accordance with my invention, the cap 100 15 is made of readily pliable material that nevertheless has some stiffness. Stiff paper or pasteboard is admirably suited for this purpose. It has a central disc-like portion 16, arranged to rest at its edge on shoulder 105 13, as well as an annular groove forming flange 17, extending up above the portion 16. The groove formed thereby conforms

with the top of bead 12, fitting over it closely. A depending flange 18 serves to define the groove. 45

The cap 15 can be inserted in the bottle 5 mouth and pressed into place by the aid of a plunger, operating not only upon the inner disc-like portion 16, but also upon the flange 17. One of the important features of my 10 invention resides in the provision of a supplementary disc 19 of stiff paper or the like, which tightly fits into the round space above portion 16 and defined by flange 17. This disc actually takes the brunt of the force 15 seating the cap 15 on shoulder 13, and prevents the cap from being harmfully distorted. Of course, a slight bulge between the disc 19 and portion 16 is very apt to occur after seating the cap, and is due to the fact that the sizes of these parts are 20 slightly larger than the corresponding spaces in which they are accommodated. In this way, a tight seal is ensured.

When the cap 15 is thus in place, the disc 25 19 effectively prevents accidental loosening of the cap in the mouth of the bottle. In order further to ensure a tight seal, I provide a series of small depressions 20 in the flange 17, arranged to cooperate with the surface of bead 12 as vacuum cups. Thus 30 when securely attached, the depressions 20 serve by air pressure to retain the cap 15 in close contact with the bead. Due to the provision of a number of such cups, tightness is yet maintained even if one or two 35 of them fail to retain their air tight quality. The cap being made from readily conformable material, it is a simple matter to ensure that these cups 20 will function in the desired manner.

40 In order to remove the cap 15, it can be turned relative to bottle 11, which will slightly loosen it. To replace the cap, it can again be turned while pressed against the bottle mouth. In this manner, the closure

can be made sufficiently tight for the needs of the average household.

In Fig. 3 I show a cap 21 having substantially the same characteristics as cap 15, except that it cannot readily be removed without tearing it or altering its appearance, thus making it adaptable for use in connection with certified milk. The cap 21 has an outer flange 22 that closely embraces the outside of bead 12 and curves inwardly around the lower portion of the bead. Thus to take the cap 21 off, it is necessary to tear it off. 55

In order to get the cap 21 on in this position, it is made as shown most clearly in Fig. 5; in this figure, it is seen that flange 22 is formed by the aid of a series of strips 23, shown flattened out except in the upper right hand corner. The adjacent edges of the strips 23 have flaps 24, which are arranged to be fastened together as by clips 25 after the strips 23 are bent to form the flange 22 and are in place on the bottle. Of course other schemes for forming the flange 22 could be used. 60

I claim:

1. In a bottle cap, means forming a closure, and a flange therefor arranged to cover the edge of the bottle opening, said flange having a plurality of small depressions therein forming vacuum cups to hold the cap in place when applied to the opening. 70

2. In a bottle cap, a covering member arranged to rest at its edges against a shoulder in the mouth of a bottle, a flange for said member forming an annular groove accommodating the edge of the bottle mouth, said flange having one or more depressions to form vacuum cups to hold the cap in place to said edge, and a disc placed over the covering member and held within the flange. 80

In testimony whereof I have hereunto set my hand.

RUDOLF WM. VON SYDOW.
